UNITED STATES PATENT OFFICE.

OZELLO R. HUNT, OF CHICAGO, ILLINOIS, ASSIGNOR OF ONE-HALF TO WILLIAM VAN
MIDDLESWORTH, OF CHICAGO, ILLINOIS.

MATTRESS.

1,034,800.

Specification of Letters Patent.

Patented Aug. 6, 1912.

Application filed December 29, 1911. Serial No. 668,560.

To all whom it may concern:

Be it known that I, OZELLO R. HUNT, a citizen of the United States, residing at Chicago, in the county of Cook and State of Illinois, have invented a new and useful Improvement in Mattresses, of which the following is a specification.

This invention pertains particularly to a detachable mattress employed in conjunction with a spring structure, such as a bed-spring, a spring-bottom for couches, and the like.

The primary object is to provide, for use on spring structures, detachable mattresses of interchangeable character, enabling any desired mattress or mattress-cover to be employed on a given spring-structure, and facilitating removal of the mattress for airing, or for repair purposes.

A further object is to provide a thoroughly practicable form of connection of adjustable character, so that no difficulty will be experienced in connecting the mattress-cover to the spring-structure, despite such variations in the spacing of the connecting devices as are likely to occur in the manufacture on a commercial scale.

The invention is illustrated in its preferred embodiment in the accompanying drawing, in which—

Fig. 1 represents a perspective view of the invention applied to a bed-spring, the view showing the mattress-cover with a portion broken away; Fig. 2, a broken vertical sectional view, taken as indicated at line 2 of Fig. 1; Fig. 3, a broken perspective view, showing a corner connection employed; Fig. 4, an inner perspective view of the same portion; Fig. 5, a perspective view of a fragment of the marginal frame rod and one of the button-studs adjustably mounted thereon; and Fig. 6, a broken perspective view, showing a modification.

A represents a spring structure; and B a mattress detachably mounted thereon. The selected spring-structure, A, is an ordinary bed-spring, having the base-frame 1, coil-springs 2 mounted thereon, and suitable means 3, tying the top-rings, 4, of the coils together. As is usual, the end-rings 4 of the marginal rows of the structure have connected therewith a marginal rod 5. The marginal bars of the base 1 are equipped with angular bracket-members 6, having

vertical arms 7 secured at their lower ends to said marginal bars and having outturned arms or flanges, 8, which carry a marginal rod or frame-member 9, upon which are shiftably pivoted mattress-connecting members 10. The members 10 are preferably in the form of glove-button studs whose shanks are secured to clips or loops 11, pivotally and slidably mounted on the rod 9. At the corners of the structure, clips 12 are secured to the rod 9, each clip comprising a piece of sheet-metal bent to angular form, the two arms embracing the corner portion of the rod and having lugs 13 clenched on the rod. Each arm of the member 12 has a slot 14 with which is slidably secured the shank of a button-stud 10.

The arms 8 of the brackets are preferably located a couple of inches above the bottom of the frame 1, and the rod 9 is secured by reducing and curving or clenching the extremities of the arms about or upon the rod. The brackets are adapted to rest upon the rails of the bed, while the base of the frame is embraced between the rails. The marginal rod 9 is disposed directly beneath the marginal rod 5, as shown.

The mattress is shown provided with a removable cover, or slip, 15, comprising, a top 16, and a skirt 17 formed of depending side and end flanges. This covers the mattress pad, or tick, 18^a, which rests upon the spring-structure; and the skirt 17 depends to near the marginal rod 9, and is equipped at its lower margin with button-sockets 18, adapted to snap on the studs 10. The members 18 may be spaced in an approximately uniform manner, as shown in Fig. 1. The skirt 17 is short enough to place a slight tension upon the springs when the skirt is buttoned to the members 10.

The adjustability of the buttons 10 not only facilitates the buttoning operation, but also insures a smooth, even condition of the mattress cover and its skirt. A comparatively small gage rod 9 suffices as a mounting device for the buttons 10, and this feature, together with the pivoting of the members 11 facilitates the buttoning operation, since a finger may be readily passed beneath the rod and behind the member 11 to support the member while the buttoning is effected. When the spring-structure is ap-

plied to a bed, the base portion is hidden by the rails, and the structure with the mattress applied appears much like a well-made box-spring. The construction is sanitary, permits airing the mattress and washing the mattress cover; and is neat and attractive in appearance.

It will be understood that the construction enables a cheap mattress-case to be used; 10 and enables the dealer to supply his customers with mattress covers of design and value to suit the tastes and financial ability of customers.

As an added feature of advantageous construction, I have shown the spring-structure provided with anchor-chains 19 which connect the upper portions of the marginal rows of coil-springs with the rods 9. These chains incline inwardly and upwardly, as 15 shown; and, as the tops of all the coils of the structure are tied together, toppling or racking of the coils is effectively obviated.

In Fig. 6, I have shown a modification, in which an angle-bar 9^a serves as a substitute 25 for the rod 9. In this modification, the angle-bar 9^a has an inturned flange mounted on brackets 6^a carried by the marginal bars of the base of the frame 1. The button studs 10 have their shanks slidably mounted in 30 slots 14^a with which the vertical flange 20 of the member 9^a is provided. Such a construction, permits ready adjustability of the studs to coincide with the button-sockets, and the angle-bar 9^a may add materially to 35 the strength of the frame of the spring-structure.

The foregoing detailed description has been given for clearness of understanding only, and no undue limitation should be understood therefrom. While the mattress 40 cover and skirt are by preference made dis- connectible from the mattress-pad, the in- vention is not limited thereto.

The invention is applicable to bed- 45 springs, and spring bottoms for various pur- poses. It may be used advantageously in connection with couches, for instance.

The feature of reducing the extremities of the arms 8, as indicated, enables the extremities to be readily curved about the rod 9, 50 thus forming the eyes 20 which support the rod.

The mode of attaching the spring cover 55 would be the same, were the mattress 18 to be omitted or placed above the cover. In such case, the skirt 17 would be suitably shortened, so that the cover would merely inclose the springs, instead of both mat- tress and springs. Where both the slip and 60 mattress are employed, they may be re- garded as a cover within the meaning of the claims.

What I regard as new, and desire to se- cure by Letters Patent, is—

1. The combination with a spring-struc- 65 ture comprising a frame and coil-springs supported thereon, of a marginal frame member equipped with adjustable fastener-members, and a cover mounted on the springs and having a depending skirt pro- 70 vided with co-acting fastener-members.

2. The combination with a spring-struc- 75 ture comprising a base and surmounting coil-springs, of frame-members disposed above said base and adjacent the marginal rows of coil-springs, button-studs slidably mounted on the same, and a cover mounted on the springs and provided with a skirt equipped with button-sockets, for the purpose set forth.

3. The combination with a spring-struc- 80 ture comprising a base and surmounting coil-springs, said base equipped with brackets having outturned flanges disposed above said base, marginal frame-members carried 85 by said flanges, fastener-members slidably connected therewith, and a cover mounted on the springs and provided with a skirt equipped with fixedly secured fastener-members adapted for engagement with said first- 90 named fastener-members.

4. The combination of a spring-structure comprising a base and surmounting coil-springs, said base equipped with brackets having outturned flanges disposed above said base, a marginal rod carried by said flanges, 95 clips slidable on said rod and equipped with button-studs, and a cover provided with a skirt equipped with button-sockets, for the purpose set forth.

5. The combination with a spring-struc- 100 ture comprising a base and surmounting coil-springs, said base equipped with brackets having outturned flanges disposed above said base, a marginal rod carried by said flanges, clips slidable on said rod and equipped with button-studs, angular corner- 105 clips secured to the corner portions of said marginal rod and equipped with button- studs, and a cover provided with a skirt equipped with button-sockets adapted to receive said button-studs.

6. The combination of a spring-structure, comprising a base and surmounting coil-springs, bracket-members having vertical 110 arms secured at their lower ends to said base and having outturned arms with reduced extremities bent to form eyes, and a marginal rod carried by the eyes of said outturned arms.

OZELLO R. HUNT.
